WEFT REPLENISHING DROP BOX LOOM

Albert A. Gordon and William M. Wattie, Worcester, Mass., assignors to Crompton & Knowles Loom Works, Worcester, Mass., a corporation of Massachusetts

Application January 8, 1934, Serial No. 705,782

4 Claims. (Cl. 139—232)

This invention relates to weft replenishing looms having a plurality of shifting shuttle boxes at each end of the lay. In certain aspects, our invention is particularly applicable to so-called "pick-and-pick" looms, in which a single pick of a given kind or color of weft may be inserted if and when desired.

In this present application, we have shown our invention embodied in a pick-and-pick loom provided with two shifting shuttle boxes at each end of the lay and arranged to pick the shuttles alternately, each shuttle moving from a lower box on one side of the loom to an upper box on the opposite side, or vice-versa.

15 In the weaving of certain fabrics, such as some kinds of upholstery, a coarse weft yarn such as a woolen yarn may be used in one shuttle and a very fine weft yarn such as a silk thread may be used in the other shuttle. Obviously the silk bobbin will contain many times the yardage of weft of the woolen bobbin and, if similarly operated, will run many times as long before weft exhaustion.

20 It is accordingly desirable to provide automatic weft replenishment for the frequently exhausted woolen shuttle, while manual replenishment of the silk shuttle is quite satisfactory.

25 It is one object of our invention to provide means for detecting the condition of weft supply in a plurality of shuttles in a drop box loom, together with means for automatically replenishing certain of said shuttles, and means for effecting loom stoppage on substantial exhaustion of weft in other shuttles.

30 In our present application, two shifting shuttle boxes are shown at each side of the loom, and two shuttles only are used, but in certain aspects our invention is not dependent on the provision of this particular number of shuttles and shuttle boxes.

35 We further provide means for automatically replenishing one shuttle when in the top box at one side of the loom and for stopping the loom for manual replenishment of the other shuttle when said other shuttle is in the top box at the 40 opposite side of the loom, each shuttle traveling from a lower to an upper box, or vice-versa, at each flight thereof.

45 A further object of our invention is to provide for horizontal weft replenishment of a shuttle while it is located above normal running position and above the path of oscillating movement of the lay end, picker and picker rod or spindle, so that a clear path for the ejected bobbin is provided.

We further provide means to render the feelers or weft detectors in our improved loom inoperative during downward movement of the associated shuttle boxes, for a reason to be disclosed.

Our invention further relates to arrangements and combinations of parts which will be herein-after described and more particularly pointed out in the appended claims.

A preferred form of the invention is shown in the drawings, in which

Fig. 1 is a front elevation of a loom embodying our improvements, with parts of the dobby shown in section;

Fig. 2 is a partial left-hand side elevation of the loom, with the drop boxes in section;

Fig. 3 is a similar partial right-hand side elevation;

Fig. 4 is an enlarged side elevation of the weft detecting mechanism shown in Fig. 3;

Fig. 5 is an enlarged front elevation, looking in the direction of the arrow 5 in Fig. 4;

Fig. 6 is an enlarged plan view of the weft detectors and parts of the loom stopping mechanism, looking in the general direction of the arrow 6 in Fig. 4;

Fig. 7 is a detail front elevation of certain parts appearing in Fig. 5;

Fig. 8 is a detail sectional side elevation, taken along the line 8—8 in Fig. 6;

Fig. 9 is a detail plan view, looking in the direction of the arrow 9 in Fig. 1;

Fig. 10 is a sectional side elevation, taken along the line 10—10 in Fig. 9;

Fig. 11 is a detail sectional front elevation, taken along the line 11—11 in Fig. 9, and

Fig. 12 is a partial left-hand side elevation, with certain parts broken away to show the drop box actuating mechanism.

Referring particularly to Figs. 1, 2, and 3, we have shown our invention embodied in a 2 x 2 pick-and-pick loom having a frame F and lay ends 20 and 21 provided with upper and lower drop boxes 22 and 23 for the lay end 20, and upper and lower drop boxes 24 and 25 for the lay end 21.

45 The loom is provided with the usual bottom or cam shaft 25 and crankshaft 26 (Fig. 3), and the crankshaft is connected to the lay with the usual links or connectors 27. The crankshaft commonly makes two revolutions for each revolution of the cam or bottom shaft 25.

50 A magazine M is mounted at the front of the loom at the left-hand side. The details of construction of the magazine form no part of our present invention and the magazine may be of 55

the general type shown in a prior patent to Gordon No. 1,766,895, issued June 24, 1930.

For present purposes, it may be stated that the magazine comprises a fixed frame work 30 in which two or more bobbin holders are mounted for vertical sliding movement. These bobbin holders are normally held in raised position but upon indication of weft exhaustion, a selected holder will be moved downward to present a bobbin in the path of a transfer member 31 (Fig. 2) supported on a rod 32 swinging about a fixed pivot 33. The rod 32 is connected by a link 34 to a head 35 having a substantially L-shaped slot 36 therein.

15 A stud 37 (Fig. 2) on an arm 38 extends into the slot 36. The arm 38 is pivoted at 39 and is connected to a second arm 40 having a cam roll 41 engaging an actuating cam 42 on the bottom shaft 25. The slotted head 35 rests on 20 a roll 43 mounted on a lever 44 pivoted at 45 and connected to a link 46.

The link 46 is connected to an arm 47 (Fig. 2) on a rock shaft 48 mounted for both sliding and angular movement in fixed bearings on the loom frame F and on the magazine M. A second arm 49 on the rock shaft 48 is connected by a link 50 to an arm 51 pivoted at 52 and having an associated arm 53.

30 The arm 53 is provided with a tension spring 54 and is connected by a link 55 to a bell crank 56 (Fig. 10) pivoted at 57 (Figs. 9 and 10). A rearwardly extending arm 58 of the bell crank 56 is provided with a depending bearing portion 59 (Fig. 11) for a sliding plunger 60 which is 35 connected by a rod or wire 61 to feeler mechanism to be described.

A chopper lever 62 is also mounted on the stud 57 which supports the bell crank 56 and is connected by a link 63 to a cam lever 64 (Fig. 2) pivoted at 65 and having a cam roll 66 engaging a cam 67 on the bottom shaft 25.

The parts are normally in the position shown in Figs. 2 and 10, with the cam roll or stud 37 (Fig. 2) positioned in the segmental portion of 45 the slot 36. When the parts are thus positioned, the stud 37 will move freely along the segmental slot 36 when the arm 38 is oscillated and no movement of the transfer member 31 will take place.

50 If, however, the weft detecting mechanism associated with the plunger 60 (Figs. 9 and 11) indicates substantial weft exhaustion, the plunger 60 will be projected under the chopper lever 62, causing the bell crank 56 to be moved in the 55 direction of the arrow a in Fig. 10, which movement, through the connections described, will shift the slotted head 35 (Fig. 2) so that the stud 37 is positioned in the offset end of the slot 36. The transfer member 31 will then be drawn 60 rearward on the next movement of the arm 38 by the cam 42.

For a more complete description of the transfer member and its actuating mechanism, reference is made to the prior patent to Gordon No. 65 1,803,181, issued October 28, 1931.

Suitable provision is also made for shifting the rock shaft 48 (Fig. 2) axially after each transfer so that bobbins will be drawn successively from different bobbin holders in the magazine M. The mechanism for shifting the rock shaft 48 axially to effect such successive delivery may be substantially as shown in the prior patent to Brown No. 1,817,124, issued August 4, 1931.

75 Any suitable or convenient mechanism may be

provided for shifting the drop boxes. In Figs. 1 and 12 we have indicated diagrammatically mechanism for alternately raising and lowering the drop boxes 22 and 23 at the left-hand side of the loom on successive picks of the loom.

For this purpose we have shown a double lobe cam 75 (Fig. 12) engaging a cam lever 76 pivoted at 77 and connected to a cord or cable 78. The cord 78 passes around a guide-roll 79 rotatable on a rock shaft 80 and then passes around guide-rolls 81 and 82 on the lay and is finally connected to the lower end of the drop box lifter rod 83.

10 The cam 75 (Fig. 12) is connected by a gear 85 and pinion 86 to the cam shaft 25 and thus makes one revolution for each four beats of the lay. Consequently the drop boxes 22 and 23 will be alternately raised and lowered by the double cam 75, with one such movement occurring for 15 each beat of the lay.

In Figs. 1 and 3 we have shown similar mechanism for operating the right-hand drop boxes 24 and 25, such mechanism comprising the double lobe cam 90, cam lever 91 and connecting rod or 20 cable 92 passing around guide pulleys 93, 94, and 95 and connected to the lower end of the lifter rod 96, all as previously described.

The cam 90 is also driven at half cam shaft speed from the cam shaft 25 through a pinion 97 and gear 98, and the cams 75 and 90 are so positioned relatively to each other that the two sets of drop boxes move substantially simultaneously, but that one set of boxes rises while the other set of drop boxes moves downward. Box movement on the detecting end of the lay may, however, begin somewhat earlier than at the magazine end and with an easier and slower motion.

We will now describe the weft detecting mechanism and the connections through which the 40 weft detectors or feelers are rendered effective to initiate weft replenishment for one shuttle, or to cause stoppage of the loom for the other shuttle.

A pair of weft detectors or feelers 100 and 101 (Fig. 4) are mounted on stands 102 and 103, which stands are secured to or formed integral with a slide 104 vertically movable in fixed guideways 105. A link 106 is pivoted at its upper end to the slide 104 and at its lower end is pivoted to a member 107 (Fig. 3) which is movable vertically with the drop box lifter rod 96. Consequently the detectors 100 and 101 are maintained at all times in horizontal alignment with the bobbins in the shuttles in the shuttle boxes 24 and 25.

The lower weft detector 100 is associated with the shuttle to be automatically replenished, this shuttle occupying the top box at the magazine side of the loom and the lower box at the opposite side.

The detectors 100 and 101 are pivoted adjacent the rear ends of slides in the stands 102 and 103, one pivot being indicated at 108 in Fig. 6. A portion of the detector 100 extends forward from its pivot and is swung sideways through a slot 109 (Fig. 4) in the side of the stand 102 when the detector slips sideways to indicate substantial weft exhaustion.

This swinging forward end of the detector 100 engages an offset portion 110 (Fig. 4) of an arm 111 (Fig. 5) pivotally mounted on a stud 112. An associated depending arm 113 is pivotally connected to the rod or wire 61 and plunger 60 (Fig. 9) previously described.

When the detector 100 engages a substantially 75

exhausted bobbin, the detector slips to the left, as viewed in Fig. 6, moving the arms 111 and 113 and rod 61 in the direction of the arrows *b* in Fig. 5, and thus projecting the plunger 60 (Figs. 9 to 11) in the path of the chopper lever 62. This initiates weft replenishment of the indicated shuttle on its return to the top box at the magazine side of the loom, all as previously described.

The upper weft detector 101 swings about its pivot 108 (Fig. 6) on indication of weft exhaustion and the forwardly extending portion of the detector is displaced sidewise through a slot 120 (Fig. 4) in the side of the upper stand 103.

The swinging forward end of the detector engages an arm 121 pivoted at 122 (Fig. 4) and extending forwardly alongside the slot 120. A rearwardly extending associated arm 123 is connected by a link 124 (Fig. 6) to a plunger 125 mounted in bearings 126 (Fig. 8) on the filling 20 fork slide 127.

An actuating member 130 (Fig. 8) is mounted on a fixed pivot 131 and is provided with an arm 132 connected by a link 133 to a lever 134 (Fig. 8) pivoted at 135 and periodically oscillated by a cam 136 on the cam shaft 25.

The actuating member 130 (Fig. 8) has an up-standing portion or lug 138 positioned to engage the plunger 125 under certain conditions, and is also provided with a hook 139 positioned to engage a hook 140 at the forward end of the usual filling fork 141 (Fig. 6).

Upon indication of weft exhaustion in the upper shuttle at the right-hand side of the loom, the detector 101 will slip sidewise, thus projecting the plunger 125 into the path of the lug 138 (Fig. 6) and causing the filling fork slide 70 to be moved forward. Such forward movement swings the knock-off lever 144 (Fig. 6) about its pivot 145, thus releasing the shipper lever 146 and causing 40 the loom to stop in the usual manner.

It will thus appear that the detector for the lower box initiates weft replenishment of the indicated shuttle after it has returned to the top box at the magazine side of the loom, while the detector 101 for the upper box causes stoppage of the loom when the indicated shuttle has returned to the top box at the right-hand side of the loom, in which position it may be conveniently replenished manually.

It is desirable that the weft detectors operate only during upward movement of the shuttle boxes 24 and 25. We accordingly provide means for withdrawing the detectors during the downward movement of these boxes. For this purpose we provide an arm 150 (Fig. 5) pivoted on a fixed pivot 151 and yieldingly pressed to the left in Fig. 5 by a tension spring 152.

At its upper end the arm 150 is provided with a ledge 153 having its upper end normally abutting the left-hand portion of the fixed guideway 105 but having its lower end spaced therefrom as indicated in Figs. 5 and 7.

An arm 160 (Figs. 5 and 6) is mounted on a fixed pivot 161 and has a pin 162 positioned to be engaged by the flange 153 on the arm 150. An associated arm 164 is mounted to swing with the arm 160 and has an enlarged end portion 165 engaging offset end portions 166 and 167 of the slides in the feeler stands 102 and 103.

As the boxes move upward, the feeler stand slide 104 moves upward, but the pin 162 clears the lower end of the flange 153 as indicated in Fig. 7 and the detectors remain in operative position. Upon downward movement of the drop 75 boxes, however, the pin 162 engages the flange

153, also as indicated in Fig. 7, and the feelers are drawn forward out of operative position during such downward movement of the drop boxes. Consequently the weft detectors are permitted to operate only on upward movement of the drop boxes and useless indications on the intervening downward movements are thus avoided.

Having thus described our invention, the operation and utility thereof will be readily understood. The weft detectors engage the shuttles alternately in the right-hand shuttle boxes, and on indication of weft exhaustion they cause the shuttle having the coarse filling to be replenished by the magazine or cause the loom to be stopped with the shuttle having the fine filling in the upper box at the right-hand side of the loom. By the use of a two-cell magazine, a double supply of bobbins is provided for the shuttle having the coarse filling, and the loom will run for a long period of time without attention by the weaver.

Having thus described our invention and the advantages thereof, we do not wish to be limited to the details herein disclosed, otherwise than as set forth in the claims, but what we do claim is:—

1. In a weft replenishing pick-and-pick loom, a lay having a pair of shifting shuttle boxes at each end thereof, a pair of shuttles, means to shift said boxes so that each shuttle will always travel between a lower box at one end and an upper box at the opposite end, a magazine adjacent the shuttle boxes at one end of the lay and holding bobbins of one characteristic of weft only, the shuttle in the upper box at the magazine end always having weft of the kind stored in said magazine and the shuttle in the lower box at the magazine end always having a second and different kind of weft, a pair of feelers adjacent the boxes at the end of the lay remote from the magazine, and a filling stop motion, the feeler which coacts with the weft in the shuttle in the top box at the feeler end of the lay being operatively connected to the filling stop motion to stop the loom on substantial exhaustion of the second kind of weft and with said shuttle in said top shuttle box at the feeler end of the lay, and the feeler which coacts with the weft in the shuttle in the lower box at the feeler end of the lay being operatively related to the magazine to effect automatic replenishment of the first kind of weft after said shuttle is received in the top box at the magazine end of the lay.

2. In a weft replenishing pick-and-pick loom, a magazine, a lay having a pair of shifting shuttle boxes at each end thereof, means to shift said pairs of boxes simultaneously but in opposite directions, whereby each shuttle travels between an upper box on one side and a lower box on the other side, a separate weft detecting feeler to indicate substantial weft exhaustion in each shuttle at the side of the loom remote from the magazine, means to cause automatic weft replenishment from the magazine on indication of substantial weft exhaustion in one shuttle, means to stop the loom on indication of substantial weft exhaustion in the other shuttle, and means to render both of said feelers inoperative as the associated shuttle boxes are lowered both feelers being operatively positioned as the boxes are raised.

3. In a weft replenishing loom, a magazine, a lay having a lay end and associated shifting shuttle boxes adjacent said magazine, means to deliver a substantially exhausted shuttle to the upper shuttle box, means to shift said boxes to

bring the upper shuttle box a full box shift above its active position, and means to transfer a bobbin horizontally to said upper box when in such raised position.

5. 4. In a weft replenishing loom, a magazine, a lay having a lay end and associated shifting shuttle boxes adjacent said magazine, means to deliver a substantially exhausted shuttle to the

upper shuttle box, means to shift said boxes to bring the upper shuttle box a full box shift above its active position and in a path of movement just below said magazine, and means to transfer a bobbin horizontally rearward to said upper box 5 when in such raised position.

ALBERT A. GORDON.
WILLIAM M. WATTIE.
